MUD BOX

William J. Miller, Los Angeles, Calif.

Application April 15, 1939, Serial No. 268,090

7 Claims. (Cl. 166—16)

This invention relates to a mud box of a type especially designed for use in connection with the pipe or tubing of a rotary drilling rig.

In drilling deep wells it is necessary to have a mud fluid in the bore to soften cuttings for removal and other purposes, such as holding down pressure that may be encountered while drilling so as to prevent a blowout which would ruin the well and endanger the crew. Quite often the lower end of a pipe or tubing or drill stem is plugged up and in removing the same from the hole the drill tube or stem is unscrewed or broken down into sections for placement in the derrick or for changing drill bits or other equipment. When removing the tube or stem with the lower end stopped up or partially stopped, the fluid in the tube or stem above the rotary with the present equipment now in use is wasted and splashed over the derrick floor after a section is unscrewed. This waste results in a material loss of the mud fluid from the bore or hole. It is an object of my invention to provide a mud box to eliminate this disadvantage.

The invention consists in the details of construction and in the combination and arrangement of the several parts of my improved mud box whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawings, wherein:

Figure 1 is a view in top plan of a mud box constructed in accordance with an embodiment of my invention;

Figure 2 is a view in side elevation of the box as illustrated in Figure 1;

Figure 3 is a view in rear elevation of the box as herein disclosed;

Figure 4 is a sectional view taken substantially on the line 4—4 of Figure 1 with the box in applied position upon a drill tube or stem;

Figure 5 is a sectional view taken substantially on the line 5—5 of Figure 4;

Figure 6 is a fragmentary view in top plan showing my improved box in open adjustment after application to or removal from the drill tube or stem.

As disclosed in the accompanying drawings, my improved box comprises an elongated back

plate 1 arcuate in cross section and which has hingedly connected, as at 2, to the longitudinal marginal portions thereof of the side plates 3 also arcuate in cross section. When the plates 3 are in closed position they coact with the back or rear plate 1 to provide a substantially cylindrical box which, when in applied position, surrounds a drill tube or stem D above and below the connection 4 between adjacent sections of the tube or stem D.

The opposite end portions of the back or rear plate 1 are provided with the inwardly disposed flanges 5 preferably welded in applied position and bolted, as at 6, to the inner face of each of these flanges 5 is an arcuate packing block 7 15 preferably of a rubber compound. Each of these blocks 7 is adapted to tightly contact with a peripheral portion of the drill tube or stem to which it is applied. The upper and lower end portions of the side plates 3 also have welded 20 or otherwise suitably secured thereto the inwardly disposed flanges 8 to the inner face of each of which is bolted, as at 10, or otherwise securely fastened the additional packing blocks 9 also preferably of a rubber compound and intended to 25 have close contact with the peripheral portions of the drill tube or stem. The several blocks 7 and 9 are so formed that when the side plates 3 are in closed position the blocks 7 and 9 coact 30 to provide packing elements entirely surrounding the tube or stem D at points, as illustrated in Figure 4, above and below the connection or joint 4 between adjacent sections of the drill pipe or stem after said connection or joint has been raised up above the rotary.

The inner marginal portions of the side plates 3 are provided therealong with the sealing strips 11 adapted to lap the adjacent marginal portion of the back or rear plate 1 when the side plates 3 are in closed position thus effectively preventing 40 leakage between the closed plates 1 and 3. The outer longitudinal marginal portion of one of the plates 3 also carries a sealing or closing plate 12 to lap an adjacent marginal portion of the second side plate 3.

The lower portion of the rear or back plate 1 is provided with a drain nipple 14 to which a hose is adapted to be attached to allow the fluid collected within the applied mud box to be returned to the well bore or other place desired. 50

It is believed to be apparent that with my improved mud box in applied position, as the upper section of the drill tube or section is unscrewed or broken down the mud fluid therein will drain out into the applied box and then 55

drain out through the nipple 14. By this a full recovery of the mud fluid is obtained and without splashing of the mud over the derrick and surfaces adjacent thereto which would endanger the crew.

The side plates 3 have secured thereto at points substantially midway their ends the rearwardly directed arms 15. The outer end portion of one of these arms 15 is pivotally connected, as at 16, to the end portions of the links 17. These links 17 extend inwardly of the plate 1 and have their adjacent end portions provided with openings 18. These openings 18 are adapted to be aligned and the lever 19 freely disposed in said holes.

This lever 19 is also freely disposed through an eye 20 carried by an end portion of a shank 21 which threads within the clevis 22. This clevis 22 is pivotally engaged with the outer end portion of the second arm 15. The lever 19 is of desired length and extends lengthwise of the back or rear plate 1 and has its upper end portion pivotally connected, as at 23, between the outstanding ears 24 carried by the upper portion of the back or rear plate 1. This lever 19 has a portion 25 extending above the pivot 23 and which portion 25 constitutes a stop for contact with the back or rear plate 1 to limit the extent of upward swinging movement of the lower portion of the lever 19. It is to be stated that this extent of swinging movement of the lever 19 also depends upon the distance between the pivot 23 and the back or rear plate 1 plus the length of the portion 25.

As the lower end of the lever 19 is swung outwardly the side plates 3 will be swung into their open positions as illustrated in Figure 6 whereupon the box may be readily placed upon the drill tube or stem D after which the lever 19 is forced inwardly and swinging the side plates 3 into their closed position with the various packing blocks 7 and 9 in close contact with the drill tube or stem above or below the connection or coupling 4.

The shank 21 provides means whereby such adjustment can be made as required to obtain the most effective tension to hold the box around the drill pipe or stem after the inner ends of the links 17 and the shank 21 engaged with the lever 19 have passed inwardly beyond the swinging center 50 of the lever 19.

In practice the extent of movement at the points of engagement of the links 17 and the shank 21 with the lever 19 is only about three inches and the distance between the pivot 23 for the lever 19 and the portion of the lever with which the links 17 and shank 21 engage is approximately three feet. Therefore, the lever 19 may be readily swung away from the rear or back plate 1 a distance sufficient to impose an approximately three inch pull upon the links 17 and the shank 21 before the stop 25 contacts with the back or rear plate 1.

It is also to be pointed out that the openings in the links 17 and in the eye 20 through which the lever 19 is directed are of diameters slightly larger than that of the portion of the lever 19 extending therethrough so that the resultant looseness of the engagement between the lever 19 and the links 17 and the shank 21 will readily allow the desired swinging of the lever 19 without binding of the parts.

From the foregoing description it is thought to be obvious that a mud box constructed in accordance with my invention is particularly well adapted for use by reason of the convenience and

facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A mud box for embracing a drill tube comprising a back plate, side plates hingedly connected to the back plate, packing blocks carried by the opposite end portions of the back plate and side plates to tightly engage the drill tube when the box is enclosed therearound, rearwardly disposed arms carried by the side plates, a lever pivoted to the back plate and extending lengthwise of said back plate, and members operatively connected with the arms and with the lever for moving the side plates upon movement of the lever toward the back plate to close the mud box and for opening said mud box upon movement of the lever away from the back plate.

2. A mud box for embracing a drill tube comprising a back plate, side plates hingedly connected to the back plate, means carried by the opposite end portions of the back plate and side plates to substantially close the ends of the box when the box is enclosed around the drill tube, rearwardly disposed arms carried by the side plates, a lever pivoted to the back plate and extending lengthwise of said back plate, and members operatively connected with the arms and with the lever for moving the side plates upon movement of the lever toward the back plate to close the mud box and for opening said mud box upon movement of the lever away from the back plate, the pivotal connection between the lever and the back plate being at a point above the 40 arms.

3. A mud box for embracing a drill tube comprising a back plate, side plates hingedly connected to the back plate, means carried by the opposite end portions of the back plate and side plates to substantially close the ends of the box when the box is enclosed around the drill tube, rearwardly disposed arms carried by the side plates, a lever pivoted to the back plate and extending lengthwise of said back plate, and members operatively connected with the arms and with the lever for moving the side plates to close the mud box upon movement of the lever toward the back plate and for opening said mud box upon movement of the lever away from the back plate, one of the members connecting the lever with an arm being so constructed and arranged to provide means for varying the tension of the contact of the blocks upon the drill tube.

4. A mud box for embracing a drill tube comprising a back plate, side plates hingedly connected to the back plate, means carried by the opposite end portions of the back plate and side plates to substantially close the ends of the box when the box is enclosed around the drill tube, rearwardly disposed arms carried by the side plates, a lever pivoted to the back plate and extending lengthwise of said back plate, members operatively connected with the arms and with the lever for moving the side plates to close the mud box upon movement of the lever toward the back plate and for opening said mud box upon movement of the lever away from the back plate, one of the members connecting the lever with an arm comprising a shank having an eye through 75

which the rod is directed, and a clevis pivotally connected to the arm, the shank threading into the clevis.

5. A mud box for embracing a drill tube comprising a back plate, side plates hingedly connected to the back plate, means carried by the opposite end portions of the back plate and side plates to substantially close the ends of the box when the box is enclosed around the drill tube,
- 10 rearwardly disposed arms carried by the side plates, a lever pivoted to the back plate and extending lengthwise of said back plate, and members operatively connected with the arms and with the lever for moving the side plates to close
- 15 the mud box upon movement of the lever toward the back plate and for opening said mud box upon movement of the lever away from the back plate, the pivotal connection between the lever and the back plate being outwardly offset with
- 20 respect to the back plate to allow the lever when moved toward the back plate to move beyond a center into locking position.

6. A mud box for embracing a drill tube comprising a back plate, side plates hingedly connected to the back plate, means carried by the opposite end portions of the back plate and side plates to substantially close the ends of the box when the box is enclosed around the drill tube,
- 25

rearwardly disposed arms carried by the side plates, a lever pivoted to the back plate and extending lengthwise of said back plate, and members operatively connected with the arms and with the lever for moving the side plates to close

5

the mud box upon movement of the lever toward the back plate and for opening said mud box upon movement of the lever away from the back plate, the pivoted end portion of the lever being extended to provide a stop for contact with the

10

back plate to limit the extent of swinging movement of the lever proper away from the back plate.

7. A mud box for embracing a drill tube comprising a back plate, side plates hingedly connected to the back plate, means carried by the opposite end portions of the back plate and side plates to substantially close the ends of the box when the box is enclosed around the drill tube, rearwardly disposed arms carried by the side

15

plates, a lever pivoted to the back plate and extending lengthwise of said back plate, and members operatively connected with the arms and with the lever for moving the side plates to close

20

the mud box upon movement of the lever toward

25

the back plate and for opening said mud box upon movement of the lever away from the back plate.

WILLIAM J. MILLER.
